UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

RECEIVING DEVICE FOR ELECTRIC TRANSMISSION.

No. 846,414.

Specification of Letters Patent.

Patented March 5, 1907.

Application filed April 10, 1905. Serial No. 254,768.

To all whom it may concern:

Be it known that I, ISIDOR KITSEE, of the city and county of Philadelphia, State of Pennsylvania, have invented certain new and useful Improvements in Receiving Devices for Electric Transmission, of which the following is a specification.

My invention relates to an improvement in receiving devices sensitive for currents—such, for instance, as are used in long-distance telegraphy, telephony, or wireless transmission.

The accompanying drawing illustrates in diagrammatic view my invention. In this drawing I have illustrated a telephonic receiver as part of the device; but it is obvious that instead of a telephonic receiver any other of the well-known devices adapted to be actuated by current impulses may be substituted—such, for instance, as a recorder, sounder, or relay.

In the drawing, A represents the primary coil of an alternating or interrupted current—such, for instance, as the primary of an inductorium. B is the secondary thereof, and b are means to connect one or more parts of the secondary with the switch C. This switch is connected, through wire 13, with one pole of a source of direct current, (here shown as the positive pole of the battery D.) The other pole of this source of current is connected, through wire 12, with the junction of the wires 9 and 11.

The terminals of the secondary B are connected, one through wire 5 and the other through wire 6, with the adjustable screw-contacts E and F, respectively. These screw-contacts are arranged in pairs, E and E' forming one pair and F and F' forming the second pair, having the air-gaps e and f, respectively, between them.

G is the receiver proper. (Here shown as part of a telephonic receiver.) The construction of the device G is the usual one in ear-phones, with the exception that instead of one coil the core near the diaphragm is provided with two coils running parallel to each other, and in the drawing these coils are designated as g and g', the terminals of the coil g being designated by the numerals 1 and 2 and the terminals of the coil g' being designated by the numerals 3 and 4. The adjustable screw-contact E' is connected, through wire 8, with the terminal 1 of the coil g, the terminal 2 of this coil being connected, through wire 11, with wire 12. The adjustable contact F' is connected, through wire 7, with the terminal 3 of the coil g', the terminal 4 of said coil being connected, through wire 9, with the wire 12. The adjustable screw-contact E is connected to one part of the line of transmission H, and the adjustable contact E' is connected to the other part of the line of transmission H'. It is supposed that the interrupted or alternating current of the necessary high potential is flowing through B, and it is supposed that the switch C touches one or the other of the contact-points b, attached to this coil B. The current flowing through this coil will divide and will flow in part through the circuit embracing wire 6, adjustable contacts F and F', with their air-gap f, wire 7, terminal 3, coil g', terminal 4, resistance r, wire 9, wire 12, battery D, wire 13, and switch C, contact b, back to the source B. The other part of the current will flow through the circuit embracing wire 5, contacts E and E', with their air-gap e, wire 8, terminal 1 of the coil g, through this coil, terminal 2, resistance r, wire 11, wire 12, battery D, wire 13, switch C, contact b, back to the source B, and if both branches of this device are of the same resistance and their other electrical conditions are equal then the current will divide in equal proportions and the coils g and g' will be equally effected by the flow of said current; but as the connection of the coils g and g' are in opposition as to each other the effect of the current-flow through g will be neutralized by g', and vice versa, and the diaphragm will therefore remain silent. Should the resistance of either one or the other of these branches be increased or decreased or should the resistance of one of the air-gaps be altered or a current from a foreign source be sent through one of these air-gaps, then the equilibrium through these two circuits will be destroyed and the receiving device (here the diaphragm of the receiver G) will be actuated. It is now supposed that a perfect equilibrium is established between the branch embracing the air-gap f and the branch embracing the air-gap e and that therefore the diaphragm of the receiver G remains silent. If now an electric impulse is sent over the part of the line of transmission indicated as H through the air-gap e to the other part of

the line of transmission H' then the perfect balance which is necessary to keep the dia-
phragm silent is destroyed, and this dia-
phragm will vibrate in accordance with
5 these disturbances of the balance.

In using this instrument it is necessary
that first of all a true balance should be es-
tablished—that is, the instrument should be
adjusted till the point is reached where the
10 receiver remains entirely silent. For this
reason I have provided the movable switch
C and the different contacts b , so that the
operator shall at will place more or less of the
15 secondary B in one or the other of the
branches of the circuit. For this reason also
I have made the contacts E and E' , as well
as the contacts F and F' , adjustable, so that
the air-gaps between them may be increased
20 at will, and for this reason I have further pro-
vided the two coils or terminals of same with
the variable resistances r .

As is well known, a source of direct cur-
rent of comparative low resistance could not
flow through an air-gap; but if the path
25 through this air-gap is made conducting
through the flow of an interrupted or alter-
nating current then the direct current will
follow the path established by such alter-
nating current and will vary in accordance with
30 the varying flow of this alternating or inter-
rupted current. As long as the equilibrium
of both branches is maintained the flow of
the current from D will be equal in both of
35 them; but the slightest variation in the flow
of the alternating or interrupted current
through e or f will change the ratio of this
flow, and I have found that even such small
40 currents as the incoming impulse of a wire-
less or telephonic transmission will produce
such change.

As stated above, this instrument may be

used in telegraphy. It may also be used in
wireless transmission, and its sensitiveness
is so great that it even will respond to tele-
phonic impulses.

45

Having now described my invention, what
I claim as new, and desire to secure by Let-
ters Patent, is—

1. In combination with means to receive
electric impulses, a receiving device opera-
tively connected with a source of alternating
or interrupted current, in a manner so as to
nullify the effect of said impulses, a source of
50 direct current, means to nullify the effect of
said direct source on said receiver, and
means to disturb the nullifying effect in ac-
cordance with the incoming impulses.

2. A receiving instrument for electric
transmission provided with two coils, each of
said coils connected to a source of alternating
or interrupted current and a source of direct
current, the action of one of said coils nulli-
fying the action of the second of said coils
60 and means to vary the nullifying effect in ac-
cordance with the impulses received.

3. In electric transmission a receiving de-
vice, a source of alternating or interrupted
current and a source of direct current, both
normally connected to said receiving device,
adjustable means to vary the flow of said
70 currents through said receiving device in a
manner so as to nullify its effect on said de-
vice, and means to receive transmitted im-
pulses, said transmitted impulses adapted to
vary said nullifying effect.

75

In testimony whereof I hereby sign my
name, in the presence of two subscribing wit-
nesses, this 6th day of April, A. D. 1905.

ISIDOR KITSEE.
